UNITED STATES PATENT OFFICE.

NICOLAS EMILIE METHLIN, OF PARIS, FRANCE, ASSIGNOR TO SCHNEIDER, & CIE.,
OF PARIS, FRANCE, A LIMITED JOINT STOCK COMPANY OF FRANCE.

APPARATUS FOR THE APPLICATION OF HYDRAULIC PRESSURE TO THE INTERIOR OF A TUBE BEING SHAPED BY THE SELF-HOOPING PROCESS.

Application filed April 4, 1925. Serial No. 20,814.

To all whom it may concern:

Be it known that I, NICOLAS EMILIE METHLIN, a citizen of the Republic of France, resident of Paris, France, have invented new and useful Improvements in Apparatus for the Application of Hydraulic Pressure to the Interior of a Tube Being Shaped by the Self-Hooping Process, which is fully set forth in the following specification.

This invention relates to apparatus for "self-hooping" of guns, and more particularly guns of small caliber, for example of 40 mm.

In U. S. Patent No. 1,338,871, granted May 4th, 1920, there is shown, described and claimed an apparatus of this general character employing a special joint between the closing devices and the tube to be "self-hooped", which joint was so constructed as to prevent any escape of the liquid while insuring the expansion of the tube over nearly the whole of its length, the ends which were not expanded, that is to say not self-hooped, and the length of which was very small, being cut away as being of no use for forming the gun barrel. According to the present invention which is designed more particularly to be employed in the self-hooping of guns of small caliber, a somewhat greater length of tube at each end can be left unexpanded and to be cut away, and, furthermore, the expansion of the tube being less it is an object of the present invention to construct a fluid-tight joint without the use of packing as employed in the aforesaid patent, that is to say, a fluid-tight joint formed directly between the closing devices and the parts of the tube which have to be cut off after the self-hooping operation.

One form of apparatus illustrating the present invention is shown in the accompanying drawings, in which

Fig. 1 is a side elevation showing the general form of the apparatus;

Fig. 2 is an end elevation of Fig. 1 looking from the left;

Figs. 3 and 3^a, taken together, show a central vertical longitudinal section on an enlarged scale illustrating the invention in detail.

As in the prior patent, mentioned above, the apparatus consists of two cross-heads A, B serving as abutments, freely movable on

suitable supports here shown as the rails D, 55 D, and connected to each other by tie bars E. One of the cross-heads B serves as a support for, or is provided with, a closing device F, while the other cross-head A is formed so as to receive a second closing device H in 60 which is formed a duct h for the admission of liquid under pressure.

According to the present invention, the end parts C¹, C² of the tube to be subjected to the self-hooping operation are prepared 65 so as to form lodgments of the closing devices comprising between the front end (H', F', respectively), the diameter of which is the same as that of the tube to be self-hooped, and the body of the device of larger 70 diameter (H², F², respectively), a bearing shoulder H³, F³, this shoulder being preferably frusto-conical. The lodgment of the closing device must be carefully polished or ground. The closing device terminates outside of the tube in the expanded head (H⁴, 75 F⁴, respectively) which bears against the respective cross-heads. The closing device which serves to admit liquid is extended beyond the head A in tubular form and engages in said cross-head. The two closing devices are constructed of a metal having a very high elastic limit, to the end that a very strong pull can be exerted upon the tie bars E and a fluid-tight joint obtained by a 80 slight penetration of the closing devices in their bearings formed by the lodgments provided at the ends C¹, C².

What is claimed is:

1. In an apparatus for the "self-hooping" 80 of metal tubes, the combination of two oppositely disposed movable cross-heads, with tube-closing plugs of metal having a high elastic limit, the diameter of the inner end portions of said plugs being the same as that of the tube under treatment and the outer portions of said plugs being of greater diameter and having annular shoulders connecting the said inner and outer portions, said plugs and the shoulders thereon forming fluid-tight contact with corresponding surfaces within the ends of the tube under treatment, and means for moving the said cross-heads towards and from each other, whereby plastic or other packing is dispensed with.

2. In an apparatus for the "self-hooping" 100 of metal tubes, the combination of two oppo-

sitely disposed movable cross-heads, with tube-closing plugs of metal having a high elastic limit, the diameter of the inner end portions of said plugs being the same as that of the tube under treatment and the outer portions of said plugs being of greater diameter and having frusto-conical shoulders connecting the said inner and outer portions, said plugs and the shoulders thereon forming

fluid-tight contact with corresponding surfaces within the ends of the tube under treatment, and means for moving the said cross-heads towards and from each other, whereby plastic or other packing is dispensed with. 10

In testimony whereof I have signed this 15 specification.

NICOLAS EMILIEN METHLIN.
